INVENTOR

Fred M. Slater

Robert G. Green
HIS ATTORNEY

UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

FLUID-PRESSURE PUMPING APPARATUS.

Application filed August 20, 1925. Serial No. 51,362.

To all whom it may concern:

Be it known that I, FRED M. SLATER, a citizen of the United States, and a resident of Easton, in the county of Northampton and State of Pennsylvania, have invented a certain Fluid-Pressure Pumping Apparatus, of which the following is a specification, accompanied by drawings.

This invention relates to fluid pressure pumping apparatus, but more particularly to apparatus of this type for automatically and intermittently discharging the liquid from a well which may be a deep well in accordance with the rise of liquid in the well.

Great difficulty is experienced in economically and efficiently pumping the liquid from a depleted or nearly exhausted oil well for instance. Because of the great depth, two-thousand feet or more for instance, and the comparatively small amount of oil which is available for recovery, at any one time, a reciprocating pump is expensive and impracticable. When a certain amount of oil is recovered, the pump must be stopped until sufficient oil has flowed into the well again to enable the pump to be used and this may take considerable time.

Furthermore, pumping apparatus of various kinds located in the bottom of the well involving valves forming component parts of the pump, are unsatisfactory because the valves are apt to get out of order or become clogged with mud or other foreign matter.

The object of the present invention is to enable the liquid in a nearly exhausted well to be readily and economically recovered by means of fluid pressure pumping apparatus which is simple and cheap to construct, and is valveless in so far as the parts at the bottom of the well are concerned.

Another object of the invention is to enable such a well to be automatically discharged by fluid pressure from time to time when the liquid has risen in the well to a given point. After each discharge the main fluid pressure supply is stopped or cut off and is not used again until the proper amount of liquid has flowed into the well. The apparatus does not require watching or hand control but is entirely automatic and dependent for operation on the back pres-

sure created in a casing forming a pump chamber adapted to be located near the bottom of the well. 55

The apparatus is shown in one of its preferred forms in the accompanying drawings, in which—

Figure 1 is a diagrammatic longitudinal sectional elevation, broken in its length, of a deep well having my apparatus applied thereto, 60

Figure 2 is an enlarged side view of the controlling valve, 65

Figure 3 is a longitudinal sectional view of the controlling valve on the line 3—3 of Figure 5 showing the valve closed,

Figure 4 is a similar view showing the valve open, and 70

Figure 5 is a transverse sectional view of the valve on the line 5—5 of Figure 4 but with the valve closed.

Referring to the drawings, the deep well A which may be an oil well, is assumed to be greatly depleted or nearly exhausted of its oil and for the purpose of recovering this oil, a casing B forming a pump chamber is adapted to be located in the well near the bottom of the well and below the level C of the liquid to which the oil will rise in the well, after a given period of time. 75

The casing B is preferably provided with the upper head D and the lower head E, and a filling pipe F as shown extends from a point G within the pump chamber near the upper head D, down through the lower head E to a point H near the bottom of the well. 80

A discharge pipe J extends from a point K within the pump chamber near the bottom head E, through the upper head D to the surface of the ground L and is preferably provided with a down turned end O discharging into a tank or hopper P. This discharge pipe J is preferably provided with a vent Q within the pump chamber near the upper head D, through which pressure fluid as compressed air, entering the pump chamber may escape to atmosphere until the vent Q is closed by the liquid rising in the pump chamber from the well through the filling pipe F. 85

A main fluid pressure supply pipe R extends from the surface of the ground to the pump chamber and terminates substantially at the point S above the height of the upper 90

105

end G of the filling pipe. As the liquid in the well rises through the filling pipe F and fills the pump chamber, the air above the liquid will escape through the vent Q until said vent Q is closed by the liquid. The back pressure then created in the supply pipe R is utilized to control the opening of the controlling means T connected to the supply pipe above ground, and automatically supply fluid under line pressure from the supply line U to the pump chamber to discharge the liquid. This controlling means T preferably in the form of a valve mechanism, includes means for continuously permitting leakage of pressure fluid down the supply pipe R to the pump chamber until discharge takes place, and in this instance, means are provided controlled by timing mechanism for cutting off the main pressure fluid supply from the main line U to the pump chamber, so that the apparatus is in readiness to permit the filling of the pump chamber again with oil or other liquid, and the well will be intermittently and automatically discharged.

The controlling apparatus indicated by the character T comprises a valve casing V to which the main supply line U is connected and to which the supply pipe R is also connected. A main valve W is located in the casing V having the head X controlling the passage of fluid from the main line U to the supply pipe R. The main valve W is preferably held normally in closed position as indicated in Figures 3 and 5 by line pressure upon the lower head Y entering the valve chamber from the supply line U through the opening a inside the main casing V.

The main valve W is preferably controlled by the auxiliary spool valve b preferably shown hollow, and having apertures c and d cooperating with the passages e and f leading from the auxiliary valve chamber to the grooves g and h respectively of the valve chamber of the main valve W. The central portion of the valve chamber of the auxiliary valve b is in constant communication with the supply line U through the port j, and the hollow bore of the auxiliary valve b, is open to atmosphere through the apertures k in the plug o. Longitudinal movement of the valve b causes the main valve W to actuate by admitting line pressure from the supply line U through port j and passage f beneath the lower head Y of the main valve while opening passage e from the upper end of the main valve to atmosphere through the aperture c in the auxiliary valve and the plug o, as indicated by the position of the parts in Figure 4, thus raising the main valve, and supplying pressure fluid from the supply line U through the aperture a in the casing around the neck p of the main valve W to the open-

ing q in the casing which communicates with the supply pipe R leading into the well.

A small leak port r is provided in the wall of the casing between the valve controlled openings a and q so that pressure fluid is constantly leaking down the well supply pipe R to the pump chamber. This constant leakage of air or pressure fluid passes to atmosphere through the hole Q in the discharge pipe J until said hole is closed by the rising oil in the pump chamber. At that time back pressure is created in the pump chamber and the supply pipe R due to the height of the liquid in the well above the vent Q augmented by the leakage referred to.

Suitable means are provided in the controller for actuating the auxiliary valve b and so adjust it that the back pressure from the well will be sufficient to cause movement of the auxiliary valve and thus actuate the main valve W. Pressure fluid from the main line U will then be admitted to the pump chamber and the oil within the pump chamber will be discharged out through the discharge pipe J to the surface of the ground thus emptying the chamber.

Timing mechanism is also provided in the controller for maintaining the main valve W open for a sufficient length of time to permit the discharge of the pump chamber and then to close the main valve automatically until the well is in readiness again to be discharged.

The casing V is provided with a plunger s having a neck t extending across the top of the main opening u of the casing V and having a head v between which and the cap w a spring x is adapted to be compressed for returning the plunger s to initial position shown in Figure 3 after it has been actuated to the position indicated in Figure 4 by back pressure. A port y connects the supply pipe R with the plunger chamber z which chamber is closed by the cap 2. The neck t of the plunger is provided with a collar 3 which cooperates with tripping mechanism operatively connected to the auxiliary valve b and also operatively connected to timing mechanism in the form of a dash pot 4 having a plunger 5 for retarding the return movement of the auxiliary valve b and thus maintaining the main valve open for the desired time.

The tripping mechanism is pivoted on the stud 6 and in the form of a toggle comprising the bell crank lever 7 having the arm 8 to which the rod 9 of the plunger 5 is pivotally connected by means of the link 10. The bell crank lever 7 is provided with a pivoted latch 12 at its upper end having a spring 13 bearing thereon and connected at one end to the lever 7 as by means of the screw or pin 14. This latch 12 cooperates with the collar 3 on the neck

t of the plunger *s* and as the plunger is forced inwardly by back pressure, the collar 3 engages the latch and rocks the bell crank lever 7 on its pivot.

- 5 Also pivoted on the stud 6 is a lever 15 connected by a link 16 to the auxiliary valve *b* at one end and at the same end provided with a lip or finger 17 engaging the fork 18 at the lower end of the bell crank lever 7. The finger 17 is narrower than the width between the fingers of the fork 18 so that there is lost motion or play between the bell crank lever 7 and the outer lever 15. The upper end of the lever 15 is connected by a 15 telescopic link 19 to the upper portion of the casing *V* and a spring 20 surrounds this link between the ends of the portions of the telescopic lever, so that as the bell crank lever 7 is rocked on its pivot the lever 15 and the link 19 which form a toggle are thrown over the center from the position indicated in Figure 3 to the position indicated in Figure 4. The lost motion connection between the lever 15 and the bell crank 25 lever 7 causes the auxiliary valve *b* to be thrown quickly in one direction or the other. The timing element including the dash pot 4 and plunger 5 causes the mechanism to return slowly to its original position. The 30 plunger 5 is loosely mounted on the end of the connecting rod 9 and a spring 21 surrounding the connecting rod bears against the collar 22 on the rod and this spring is compressed as the arm 8 of the bell crank 35 lever 7 is raised so that the oil about the plunger 5 may pass freely through the plunger apertures 23 and into the lower portion of the dash pot 4. The spring 21 before compression, forces the plunger rod 9 downwardly and the collar 22 closes the plunger holes 23 so that the oil in the lower part of the dash pot 4 is forced back through the passage 24 into the oil reservoir 25. The 40 rate of movement of the plunger 5 is controlled by the needle valve 26 so that the timing mechanism may be set for any desired time in which to permit the well to discharge.

In the operation of the device, the oil entering the well will rise in the filling pipe *F* and pass to the pump chamber in which the level will rise until the vent *Q* is closed. The back pressure hereinbefore referred to acting upon the controlling plunger *s* will 55 force said plunger to the left as the drawings are viewed and the collar 3 on the

plunger neck *t* will engage the latch 12 and rock the bell crank lever 7 upon its pivot which movement will in turn rock the lever 15 and the auxiliary valve *b* will be actuated 60 to admit pressure fluid beneath the main valve *W* and raise said valve. Pressure fluid from the main line *U* will then be admitted to the pump chamber through the pipe *R*. The spring *x* will return the plunger *s* to the initial position and the collar 3 will pass backwardly over the latch 12. The spring 21 on the dash pot plunger rod 9 will force the dash pot plunger 5 downwardly in the dash pot at a rate determined by the 65 setting of the needle valve 26, thus returning the auxiliary valve *b* to initial position which will cause the closing of the main valve *W*. The apparatus is then in condition to be again actuated to embody the 70 pump chamber when the pump chamber has filled with oil.

I claim:

1. Fluid pressure pumping apparatus for automatically discharging liquid from a 80 well in accordance with the rise of liquid in the well, comprising a casing located in the well into which the liquid is permitted to enter, means controlled by the back pressure in the casing for automatically discharging the casing by main pressure fluid, said discharging mechanism including a main valve, an auxiliary valve controlling the main valve, and a back pressure valve 85 controlling the auxiliary valve. 90

2. Fluid pressure pumping apparatus for automatically discharging liquid from a deep well in accordance with the rise of liquid in the well, comprising a casing located in the well into which the liquid is permitted to enter, a controller controlled by the back pressure in the casing for automatically discharging the casing by main pressure fluid, said controller comprising a main valve, an auxiliary valve controlling the main valve, 95 a controller plunger subject to back pressure, operative connections between the controller plunger and the auxiliary valve, and a timing element operatively connected to said connections between the plunger and the auxiliary valve, said timing element having fluid retarding means, and means for varying the time in which said timing element acts. 100

In testimony whereof I have signed this 110 specification.

FRED M. SLATER.
